UNITED STATES PATENT OFFICE.

ALEXANDER McDONALD, OF DULUTH, MINNESOTA.

DESIGN FOR A DISPLAY-STAND.

45,692.

Specification for Design.

Patented Apr. 28, 1914.

Application filed February 10, 1914. Serial No. 817,941. Term of patent 7 years.

To all whom it may concern:

Be it known that I, ALEXANDER McDONALD, a citizen of the United States, residing at Duluth, in the county of St. Louis and State of Minnesota, have invented a new, original, and ornamental Design for a Display-Stand, of which the following is a specification, reference being had to the accompanying drawing, forming part thereof.

The figure is a perspective view of a display stand, showing my new design.

I claim:

The ornamental design for a display stand, as shown.

ALEXANDER McDONALD.

Witnesses:

GEO. C. ROSS,
H. B. SHILER.
